Inventor,
Charles E. Kew,
By my Power and Duly.

UNITED STATES PATENT OFFICE

CHARLES E. KEW, OF CHICAGO, ILLINOIS.

SHELF AND DRAWER SUPPORT.

Application filed July 1, 1925. Serial No. 40,798.

To all whom it may concern:

Be it known that I, CHARLES E. KEW, a citizen of the United States, residing at Chicago, in the county of Cook and State of Illinois, have invented a new and useful Improvement in a Shelf and Drawer Support, of which the following is a specification.

My present invention relates to improvements in shelf and drawer supports and has for its object the provision of an extremely simple support which will be economical of manufacture and installation and when installed will dependably remain in position. Moreover, as will be hereafter seen, the support may be given the necessary form to secure a desired friction between the drawer and the structure within which it slides so as to overcome any tendency to rattle where vibration is present, for instance upon a railroad train or in a ship, and, moreover, the friction so produced will serve, also, to secure the drawer in an in or out, or in any intermediate position, as may be desired.

I attain the aforementioned objects by means of the structure illustrated in the accompanying drawing, in which—

Fig. 1 is a section through the structure with which the support is assembled showing the support in full lines.

Fig. 2 is a front elevation of the structure shown in Fig. 1 with the drawer in position.

Fig. 3 is a section similar to that shown in Fig. 1 of a modified form of support.

Fig. 4 is an elevation of the structure shown in Fig. 3 with the drawer in position.

Fig. 5 is a section similar to that in Figs. 1 and 3 in which the form of support shown in Fig. 3 is secured to the drawer body instead of the casing and a channel is provided in the casing for the receipt of the support.

Fig. 6 is an elevation of the structure shown in Fig. 5.

The casing within which the drawer slides and is supported may have any usual form, such casing being typically shown in the drawing as composed of the vertical side walls, 7 and 8, and vertical rear wall, 9. A recess, or bore, 10, is provided upon the same, or substantially the same, horizontal plane in the side walls and rear wall. The support itself comprises a spring wire, or rod, 11; and, in the form shown in

Figs. 1 and 2, the wire, 11, is bent intermediate its ends to form a stud, or projection, 12, for insertion into the recess, 10, in the rear vertical wall. The opposite ends of the wire, 11, after forming the stud, are 60 diverged and brought forward and, preferably, looped at 13, and then bent laterally to provide the studs, or projections, 14, which, respectively, enter recess, 10, in opposite side walls, 7 and 8. The spring of 65 the portion of the rod, or wire 11, between the studs or projections, is sufficient to retain the support definitely in assembly with the walls and by giving the wire, or rod, 11, a desired upward bow, any degree of 70 friction between the drawer and the top of the casing or an adjacent support can be secured.

In the modified form of my invention, shown in Figs. 3 and 4, I provide two recesses, 10^a, in each side wall, 7 and 8. The support, in this case, is in two parts, each part consisting of two studs, or projections, 14^a, connected by a length of spring wire, or rod, 11^a. In this form, also, the assembly 75 between the recesses and the support is rendered dependable by reason of the spring connection between the studs. And, also, in this form friction may likewise be obtained between the drawer and the casing 80 by bending the connecting piece, 11^a, upwardly, as shown in Fig. 4, a desired distance.

In the further modified form, shown in Figs. 5 and 6, the same form of support 90 as shown in Figs. 3 and 4, is attached by inserting studs, 14^b, in the recesses, 10^b, provided in the side walls of the drawer body instead of in the side walls of the casing. In this modified form, grooves, 15, are provided in the opposite side walls, 7 and 8, 95 in which the outer ends of the studs, 14^b, and the connecting piece, 11^b, slide. In this form of my invention, also, a desired degree of friction is developed between the drawer 100 and the casing by bowing the connecting portion, 11^b, of the support both horizontally and vertically as shown in Figs. 5 and 6.

Having described my invention, what I claim as new and desire to secure by Letters 105 Patent, is—

1. In combination with a casing to receive a shelf or drawer provided with spaced recesses in a common plane, a support having studs adapted to enter said recesses and 110

spring connections extending between said studs formed to create tension between said studs and the respective recesses with which they are assembled.

5 2. In combination with a casing to receive a drawer provided with spaced recesses in a common plane, a drawer and a support having studs adapted to enter said recesses and

spring connections extending between said studs formed to create tension between said studs and the respective recesses with which they are assembled, said spring connections being bowed to create pressure between said drawer and said casing. ¹⁰

CHARLES E. KEW.
